LEATHER GLAZING MACHINE

Filed June 11, 1927

Patented May 21, 1929.

1,714,243

UNITED STATES PATENT OFFICE.

FRANCIS JOSEPH ROBINSON, OF RICHMOND HILL, ONTARIO, CANADA.

LEATHER-GLAZING MACHINE.

Application filed June 11, 1927. Serial No. 198,043.

My invention relates to improvements in leather glazing machines, and the object of the invention is to devise a machine for glazing or rolling leather, which is so constructed that it will not warp and will always run true and be positive in its movement, and which prevents the burning of the leather during the operation of glazing, and it consists essentially of the arrangement 10 and construction of parts as hereinafter more particularly explained.

Fig. 1 is a side elevation of my device with the parts broken away to exhibit the construction thereof.

15 Fig. 2, is a plan view of the bed.

Fig. 3, is a detail view of the glazing member.

Fig. 4, is a front elevation of the head block and co-acting parts.

20 Fig. 5, is a sectional view through Figure 4.

Fig. 6, is a sectional detail on line 6—6 Figure 1.

25 Fig. 7, is a detail of the connection between the head block 9 and rocker 9°, and

Fig. 8 is a sectional view on line 8—8 Figure 5.

30 In the drawings like characters of reference indicate corresponding parts in each figure.

The base 1 of the machine is provided with an upwardly extending pair of spaced apart substantially triangular members 2 and 3. Between the members 2 and 3 is 35 located a plate 5 rigidly secured between the members 2 and 3 and on which is journaled a rocker spindle 4 by means of brackets 6. Between the members 2 and 3 is secured a head block 9, such head block being channel 40 shaped as clearly indicated in Figure 5, and provided centrally with a slotted opening 9° to the lower face of which are secured rocker members 9° in spaced apart position as clearly indicated in Figure 5.

45 The rocker members 9° have arc-shaped outer surfaces against which the plate 10 forming the head of the spindle 11 bears. The plate 10 is provided with a central opening 11° at each side of which are located 50 flange portions 12 having orifices 13 in transverse alignment in which are journaled the trunnion ends 15 of the rocker spindles 14. The rocker spindle 14 is provided with diametric orifices 16.

55 The plate 5 is also provided with a central orifice 5° in axial alignment with the

orifice 11° of the plate 10. At each side of the orifice 5° are located the brackets 6 on which the rocker spindle 4 similarly formed to the rocker spindle 14 is mounted. Through 60 the orifices of the spindle 14 and the orifices 14° of the rocker spindle 4 extend bolts 18.

The forward end of the head block 9 and the rear end of the plate 10 are connected by link rods 20. Between the lower portion of 65 the spindle 11 and the front and rear portions of the plate 10 extend braces 11°. Pivottally mounted on the lower end of the spindle 11 as indicated at 22 is a glazing tool holder 21.

70 The glazing tool 25 which is in the form of a solid cylinder of glass is held between the clamping plates 23 and 24 provided with arc-shaped lower ends 23° and 24° which are together of greater amplitude than a semi-circle so as to grip the glazing tool. The members 23 and 24 are clamped together and to the holder 21 by a bolt 26.

75 The machine is operated from a shaft 27 upon which is mounted a crank wheel 29 80 provided with a crank pin 30. Upon the crank pin 30 is pivotally mounted an arm 31 which is rigidly secured by a bolt 32 to the holder 21. The opposite end of the arm 31 is provided with two plates 33 and 34 85 forming a receiving jaw into which fits the neck 35 provided with a head 36 having an orifice through which the crank pin 30 extends. Through the plates 33 and 34 and neck 35 extends a bolt 37 so as to permit of a 90 swinging transverse movement of the head on the end of the arm 31.

A bed for the material to be glazed is provided with a base 38 upon which the bed body 39 is carried and which is in the form 95 of a hollow casting as clearly indicated in Fig. 6.

100 A water tank 40 is provided which is preferably supported on the base of the member 2 and is filled with water to act as a cooling medium for the bed 39, such water being circulated thereto by the pipe 41 leading into one side of the bed and returning by the pipe 41. The hollow bed 38 is provided with a central partition 38° which extends from one end of the bed to a point in proximity to the opposite end of the bed as clearly indicated in Fig. 1. The water travels into one end of the bed by the pipe 41 and longitudinally of the bed so as to 105 pass the end of the partition 38° and then travel in the reverse direction longitudinally 110

of the bed to pass out through the pipe 41^x to return to the water tank 40.

The upper face of the bed 39 is provided with a leather cover 42 upon which the skin 5 to be glazed is laid during the operation of glazing or rolling.

It may be pointed out that the rockers 9° are adjustably connected to the head block 9 so that they may be adjusted independently 10 and thereby brought to a true position so that they will operate evenly during the running of the machine. Such connection comprises a small slot 43 formed at each end of the head block 9 over each rocker 9°.

15 Into each rocker member 9° is mortised a nut 46. A cap screw which passes down through the slot 43 is screwed into the nut 46. By loosening the cap screw 47 the rocker may be readily adjusted longitudinally 20 so that both rockers are quickly brought to an aligned position.

In operating my machine the skin to be glazed is held upon the bed 39 by the operator and the shaft 27 revolved, the crank pin 25 of the crank wheel 29 carrying the arm 31 longitudinally and thereby reciprocating the spindle 11.

During the forward movement of the arm 31 the glazing holder 21 is thrown upward 30 on the pivot indicated at 22 thereby carrying the glazing tool 25 away from the leather to be glazed during the upward stroke of the spindle 11 swung upward by the longitudinal movement of the arm 31.

35 During the reverse movement of the arm 31 the holder 21 is necessarily drawn downward into engagement with the leather and travels thereover during the downward stroke of the spindle 11 and thereby performs 40 the glazing operation, the plate 10 rocking upon the rockers 9° backward and forward during this operation, being connected to the head block 9 by means of the link 20 as hereinbefore described.

45 From this description it will be seen that I have devised a machine which may be readily adjusted to operate absolutely true and be positive in its operation, and at the same time provide simple means which will 50 prevent the burning of the skin through the frictional operation of the glazing tool thereagainst.

What I claim as my invention is:

1. In a leather glazing machine, the combination with the bed plate and glazing tool mounted to reciprocate over the bed plate, of a water cooling device adapted to circulate water continuously through the bed plate to

compensate for the heat generated by the glazing tool in frictional contact with the skin on the bed plate.

2. In a leather glazing machine, a bed plate comprising a hollow casting having a central flange extending longitudinally of the interior thereof from one end to a point 65 in proximity to the opposite end, and means for feeding water into the interior of the bed plate at one side of such central flange to pass longitudinally thereof and past the flange end to the opposite side of the flange 70 and longitudinally in the reverse direction to the outlet.

3. A leather glazing machine comprising a base member, side standards extending upward therefrom, a head block secured between the standards, rocker members carried upon the lower face of the head block, a spindle plate bearing upon the rockers, a spindle extending downward from the plate perpendicular thereto, link bars connected at one end to the forward end of the head block and at the opposite end to the rear end of the plate at each side thereof, a glazing tool holder pivotally connected to the lower end of the spindle, a crank wheel 80 provided with a crank pin, an arm swung upon the pin at one end and connected to the tool holder at the opposite end and adapted to reciprocate the tool holder and spindle as the crank wheel revolves, and means for adjusting the rocker members independently 85 longitudinally.

4. A leather glazing machine comprising a base member, side standards extending upward therefrom, a head block secured between the standards provided with longitudinal slots, rocker members carried upon the lower face of the head block, securing means extending through the slots of the head block into the rocker members to clamp the rocker members and head block together in longitudinally adjusted position, a spindle plate bearing upon the rockers, a spindle extending downward from the plate perpendicular thereto, link bars connected at one end to the forward end of the head block and at the opposite end to the rear end of the plate at each side thereof, a glazing tool holder pivotally connected to the lower end of the spindle, a crank wheel provided with 95 a crank pin, an arm swung upon the pin at one end and connected to the tool holder at the opposite end and adapted to reciprocate the tool holder and spindle as the crank wheel revolves.

FRANCIS JOSEPH ROBINSON.
